DISPENSER FOR POWDERED MATERIAL

Jay Doblin, Chicago, Ill., assignor to Colgate-Palmolive Company, New York, N.Y., a corporation of Delaware

Filed Dec. 16, 1965, Ser. No. 213

Term of patent 14 years

(Cl. D44—22)

FIG. 1

FIG. 2

FIG. 4

FIG. 3

FIG. 5

FIG. 1 is a front elevational view of a dispenser for powdered material showing my new design, the rear, not shown, having the same appearance;

FIG. 2 is a side elevational view thereof;

FIG. 3 is a top plan view thereof;

FIG. 4 is a bottom view thereof; and

FIG. 5 is a front elevational view of a dispenser for powdered material showing another form of my design wherein the front face only is provided with the surface ornamentation shown.

I claim:

The ornamental design for a dispenser for powdered material, as shown and described.
